UNITED STATES PATENT OFFICE.

MILTON CLARK, OF NEW YORK, N. Y., AND JAMES T. COWLEY, OF BALTIMORE, MARYLAND.

STORE-SERVICE APPARATUS.

SPECIFICATION forming part of Letters Patent No. 312,088, dated February 10, 1885.

Application filed January 10, 1885. (No model.)

To all whom it may concern:

Be it known that we, MILTON CLARK, of New York, in the county of New York and State of New York, and JAMES T. COWLEY, of 5 Baltimore, in the county of Baltimore and State of Maryland, have invented certain new and useful Improvements in Store-Service Systems; and we do hereby declare that the following is a full, clear, and exact description 10 of the invention, which will enable others skilled in the art to which it appertains to make and use the same, reference being had to the accompanying drawings, and to the letters of reference marked thereon, which form 15 a part of this specification.

This invention relates to cash and parcel carrying systems for service in stores, and has for its object to provide a system possessing the greatest simplicity, and one that will operate with utmost effectiveness in the transmission back and forth of cash or purchased articles.

The invention consists in a system constructed substantially as hereinafter described, and 25 in other details, which also will be pointed out hereinafter.

Referring to the annexed sheets of drawings, Figure 1 represents in side elevation a system constructed in accordance with our invention, 30 and Fig. 2 represents a plan view thereof. Figs. 3, 4, 5, and 6 are views in detail to show the construction of certain parts.

A system constructed according to our present invention comprises in its structure a series of horizontal ways, A, that radiate from the cashier's desk B to the counters or stations C of the several salesmen. These tracks are fixed at their ends to support a, depending from the ceiling, and which are provided 35 at their ends with devices b, by which the slack in the track or way can be from time to time taken up. The tracks extend to within a short distance of their destination, and the completion of their circuit or line is made up 40 of supplemental portions c, flexible automatic devices b, by which the car is received and lowered at the terminals, and again elevated upon and given an initial impetus to travel the track, and adjustable means for varying 45

the inclination or position of the supplemental portions, and the automatic receiving devices.

In the drawings, the supplemental portions c have one of their ends attached to the opposite ends of the supports a, to which the tightening devices b are arranged for the main track, the passage of the car over the short intervening part of the support not being at all interrupted, and the opposite ends of such supports are attached to a jointed or hinged arm, which forms a part of the adjustable arm f, which moves vertically on a bar, g, that depends from the ceiling at the ends of the tracks. At the clerk's end we have represented two ways in which the adjustment of the arm f may be effected, one way being by 65 a cord, i, attached to the part h thereof, having an elongated hole, by which it is permitted movement on the bar g, and passing upwardly over a pulley, i', situated at the upper end of said bar, and the other way being 70 effected by the same cord that acts to receive the car, and also by which it is elevated and delivered upon the main track. In the latter instance the cord i' passes between two pulleys, 1 2, having their bearings in f, 75 and thence over a pulley, 3, borne upon the side of the bar g, as shown. When the car is to be elevated from the fallen position, (shown in dotted lines,) the cord i' is pulled downwardly, whereupon the tension brought to bear 80 raises the supplemental portion to an upward incline, the cord at the same time being given an incline greater than said portion, and the car consequently descends by gravity upon the main track, the impetus thus given it being 85 sufficient to carry it to the opposite end of the track. The degree of inclination necessary to carry it back and forth can be easily regulated by the adjustable mechanism. The relative positions of the devices at the opposite 90 ends of the track during the transmission of the car from the clerk to the cashier are as represented in Fig. 1, and when, for instance, the car has been forwarded from the clerk to the cashier and the impetus given it should 95 be barely sufficient to carry it to the point x at the opposite end, it will, having reached that point, be assisted forward by the down-

wardly-inclined portion *c* at the end. On the return of the car to the clerk by the cashier the relative positions of the devices at each end are simply reversed. The pulley 2 guides 5 the cord *i*² and continues the action of elevating the car as it (the cord) is being drawn up-
on to elevate the car, as it is evident that in this action the said cord would leave the pulley 1, and projecting from the side of the bar 10 *g* is a bifurcated arm or other device, 6, to which the said cord is fastened when the bar *f* has been elevated, thereby preventing the latter from falling back of its own weight until permitted to descend by the operator. At 15 the cashier's end the manner of elevation or adjustment is shown in yetanother way, which is done by means of a pulley, 4, moving upon or against a vertical rod or bar (not shown) located in a rectangular frame, *k*, secured to 20 the support *g* at the end. In this instance the pulley 4 has its bearing in the end of bar *f*, and as the cord *i* is pulled upon the said pulley moves upward, thus giving an incline to bar *f*, the cord being secured in the device 6 25 to prevent return of the parts until released by the operator. When a separate cord is employed for adjusting, as represented at *i*, the pulley 2 may be dispensed with; but where the receiving and elevating cord *i*² is em- 30 ployed to perform, in addition to its own function, that of cord *i*, then the pulley 2 is preferred, as it acts as a guide or stay for the cord. It will be observed that the pulley 1 serves to assist in maintaining the weight of the 35 bar *f*, and, further, assists in the operation both of adjustment and the incline of the flexible portion.

Upon reference being made to the enlarged detailed figures the construction of the several parts will be fully understood, we having 40 claimed such devices, broadly, in other connections in separate applications for patents.

The general subject-matter of receiving the conveyer from a track and restoring it to the same track from which it was received is not 45 claimed herein, broadly, as that forms the subject of an application now pending.

Having thus described our invention, what we claim is—

50 1. The combination of a main horizontal

track, supplemental portions at each end, automatic flexible receiving devices, and mechanism for inclining such supplemental portions and receiving devices from the main track at different angles, substantially as described. 55

2. The combination, with the main track, of a supplemental portion at one or both ends adapted to be raised and lowered out of line with said main track, the flexible portions, and mechanism, as described, whereby the parts are operated, substantially as described. 60

3. The combination, with the main horizontal track, of the supplemental portions *c*, flexible portions *i*², adjustable bar *f*, having jointed 65 arm and bearing pulleys 1, 2, the bar *g*, bearing pulleys *i*¹ and *3*, and the cord *i*, all substantially as described. 70

4. The combination of the main track, the supplemental portions, the flexible elevating and receiving devices, and the adjustable arm provided at its ends with an elongated hole, whereby it is free to be moved vertically, and mechanism for operating the same, substantially in the manner and for the purpose de- 75 scribed. 75

5. The combination, with the main track and the supplemental portions thereof, of intermediate supports connecting the two, and tightening devices to which the ends of such 80 main and supplemental tracks are secured, substantially as described. 80

6. The combination, with the main track and supplemental portions and flexible raising and lowering portions, of the bar *f*, provided with 85 slotted head, the depending bar on which said head works, and means whereby the same is adjusted, substantially as described. 85

7. The combination, with the main track and supplemental and flexible portions, of the bar 90 *f*, bearing the pulleys 1, 2, and the cord *i*², substantially as described. 90

In testimony that we claim the foregoing as our own we affix our signatures in presence of two witnesses.

MILTON CLARK.
JAS. T. COWLEY.
